COMBINED DETECTOR AMPLIFIER CIRCUITS

Adrianus Johannes Heins van der Ven, Jan van der Mark, and Bernardus Dominicus Hubertus Tellegen, Eindhoven, Netherlands, assignors to Radio Corporation of America, a corporation of Delaware

Application December 8, 1933, Serial No. 701,474
In Germany December 2, 1932

2 Claims. (Cl. 250—27)

This invention relates to a coupling arrangement for rectifying high frequency oscillations with subsequent amplification and more particularly to a combined detector amplifier arrangement. The invention is particularly adapted to arrangements wherein rectification occurs in a circuit comprising a rectifier and a condenser which condenser offers substantially no resistance to high frequency currents, one pole of this condenser being connected, without the interposition of high frequency resistances, to the electrode of the rectifier having a constant potential and the other pole being connected to the controlling grid of the amplifier.

It is imperative that no high frequency oscillations are set up at the grid of the amplifier placed behind a detector, since these oscillations may cause a small stability of the arrangement. This drawback manifests itself more particularly with superheterodyne receivers. By using the above arrangement one obtains already that extremely small tensions are set up at the controlling grid. In spite thereof, part of the high frequency voltages impressed on the detector will still be present in the input circuit of the low frequency amplifier, because the said condenser, which offers substantially no resistance to high frequency currents, together with the capacity of the diode forms a potentiometer over the input circuit of the detector. The part of the high frequency voltages thus set up at the condenser, is supplied to the grid of the amplifying tube.

The present invention provides means for avoiding that high frequency voltages are set up at the grid of the amplifier placed behind the detector. This is achieved by inserting in the arrangement set out a capacity between the grid of the amplifying tube and the electrode of the rectifier which electrode has no constant potential, said capacity having such a size that the capacities C_1 , C_2 , C_3 and C_4 form a balanced bridge, C_1 denoting the capacity of the condenser inserted in this rectifier circuit, C_2 the coupling capacity through which this condenser is connected to the controlling grid of the amplifying tube, C_3 the capacity placed between the grid of the amplifying tube and the electrode of the rectifier which has no constant potential, and C_4 designating the capacity of the rectifier.

The invention will be more clearly understood by reference to the accompanying drawing representing, by way of example, one form of construction thereof.

In the drawing 1 denotes a united detector and amplifying tube comprising a cathode 2. This

cathode which may be constructed as an equi-potential cathode, is common to the rectifier and the amplifier. By 3 is designated the anode of the rectifier and by 4 the controlling grid of the amplifier which may comprise, moreover, a protecting grid 5 and an anode 6. In the input circuit of the rectifier is inserted a tuned circuit 7 which is connected on one hand directly to the anode 3 of the rectifier and on the other hand through a condenser 8 and a leakage resistance 9 to the cathode of the rectifier.

The end of the condenser 8 which is not connected to the cathode is connected to the controlling grid of the amplifying tube through a condenser 10. A negative grid voltage can be supplied to the controlling grid of the amplifying tube through the resistance 11 which is connected to a point having a negative potential with respect to the cathode. The capacity of the rectifier may be denoted by the condenser 12 which is indicated in dotted lines on the drawing.

According to the invention a condenser 13 is inserted between the anode 3 of the rectifier and the grid 4 of the amplifier which condenser has such a size that the total capacity inserted between this anode and said grid has a value

$$\frac{C_2 \times C_4}{C_1}$$

C_2 denoting the capacity of the condenser 10, C_1 the capacity of the condenser 8 and C_4 designating the capacity of the condenser 12.

Preferably the tube used in this arrangement is equipped with an equi-potential cathode which slightly projects from the electrode system of the amplifier and is surrounded at this point with a small auxiliary anode which serves as anode of the rectifier system. In a suitable form of construction of such a system the capacity C_4 has a value of 5 cm. By giving C_1 , C_2 and C_3 a value of 500 cm. 1500 cm. and 15 cm. respectively, a considerable decrease of the high frequency voltage at the grid of the amplifying tube is achieved.

We claim:

1. In combination, a combined detector amplifier comprising an electronic tube provided with a cathode and a plurality of cold electrodes, said tube having its cathode and one of its cold electrodes arranged to serve as a diode rectifier, a circuit arrangement for the diode rectifier comprising a connection between the rectifier cold electrode and the cathode, said connection including means for impressing high frequency signal currents on said circuit and a first condenser in series, a resistor shunted across said

- 5 first condenser, an amplifier input circuit for said tube comprising a connection from a second cold electrode thereof to the cathode, said connection including a second condenser in series with the arrangement comprising the first condenser and shunted resistor whereby the rectified voltage developed in the diode circuit is impressed upon the amplifier input circuit, means including a third condenser for connecting the second cold electrode to the first cold electrode, an amplifier output circuit for said tube comprising a connection including a source of current between a third cold electrode of the tube and the cathode thereof, there being inherent capacity between the first named cold electrode and the cathode, said third condenser being proportioned so that the total capacity inserted between the first cold electrode and the second cold electrode has approximately the value
- 10
- 15
- 20

$$\frac{C_2 \times C_4}{C_1}$$

where C_2 denotes the capacity of the second condenser, C_1 the capacity of the first named condenser and C_4 the inherent capacity between the first named cold electrode and the cathode.

- 25 2. In a combined detector amplifier, an electronic tube provided with a cathode and a plurality of cold electrodes, said tube having its cathode and one of its cold electrodes disposed to serve as a diode and the cathode and the other cold electrodes arranged so as to serve as an amplifier, external circuits for forming a diode rectifier circuit and an amplifier circuit, the diode
- 30

5 circuit comprising a connection including a first condenser between the diode cold electrode and the cathode, the amplifier being provided with an input circuit and an output circuit, said input circuit comprising a connection including a second condenser and the first condenser in series between a second cold electrode and the cathode, means for impressing a carrier wave signal upon said diode circuit, means for impressing the rectified voltage developed in the diode circuit upon the amplifier input circuit, there being inherent capacity between the diode cold electrode and the cathode, a third condenser connected between the second cold electrode and the first cold electrode, said first, second and third condensers and said inherent capacity forming a four arm capacity balanced bridge circuit, the third condenser having a capacity value such that the total capacity between the diode cold electrode and the second cold electrode is approximately equal to

10

15

20

$$\frac{C_2 \times C_4}{C_1}$$

25 where C_2 denotes the capacity of the second condenser, C_1 the capacity of the first condenser and C_4 the inherent capacity between the diode cold electrode and the cathode.
